DESIGN.

—o—
L. H. MARSTON.
ORGAN CASE.

No. 19,099.

Patented May 14, 1889.

UNITED STATES PATENT OFFICE.

LOUIS H. MARSTON, OF CHICAGO, ILLINOIS.

DESIGN FOR AN ORGAN-CASE.

SPECIFICATION forming part of Design No. 19,099, dated May 14, 1889.

Application filed March 1, 1889. Serial No. 301,707. Term of patent 3½ years.

To all whom it may concern:

Be it known that I, LOUIS H. MARSTON, a citizen of the United States, residing at Chicago, county of Cook, and State of Illinois, 5 have invented and produced a new and original Design for an Organ-Case, set forth in the following specification, reference being had to the accompanying engravings, forming a part thereof.

10 The distinguishing feature of this design is found wholly in the key-board end cheek, A. This cheek is rectangular in general outline, and is prolonged upward well above the plane of the key-board, its extent above that plane 15 being as great as its entire extent below that plane. Its upper outline is defined by the narrow horizontal entablature B, which, surmounting at its forward end the vertical pilaster or pillar-like configuration of the forward 20 edge of the cheek, causes the latter to present a bold and massive front, and the cheek being thus rendered of full width at the top adds largely to the impression of depth from front to rear and thereby of massiveness to 25 the entire organ end. Subordinate to this leading architectural effect of boldness and massiveness, and as a relief or foil to that effect, this design includes the open-work D, which occupies a triangular space at the upper 30 forward part of the cheek, such space being included above and bounded rearwardly and downwardly by a line which might be

drawn across the upper part of the cheek diagonally downward from rear to front. The openings of such open-work have their limits 35 along such oblique line, and thereby suggest such line to the eye, and thus define and suggest a secondary upper marginal outline for the cheek differing from the principal and actual upper outline, which is bold and prominent, as described, in being receding and unobtrusive. In the combination of these two effects consists the characteristics of this design.

I claim—

45 The design for an organ-case herein shown and described, which is characterized by a key-board end cheek extending well up above the level of the key-board, having at the upper part the full width and having open-work occupying a triangular space at the upper forward part, the lower limits of the openings of such open-work being located in a line which might be drawn across the upper end of the cheek diagonally downward from rear 50 to front, substantially as set forth.

In testimony whereof I have hereunto set my hand, in the presence of two witnesses, at Chicago, Illinois, this 25th day of February, 1889.

LOUIS H. MARSTON.

Witnesses:

CHAS. S. BURTON,
JEAN ELLIOTT.
